UNITED STATES PATENT OFFICE.

WILLIAM C. CAMENISCH, OF CHICAGO, ILLINOIS.

DESIGN FOR A FIREPLACE-FRONT.

SPECIFICATION forming part of Design No. 29,716, dated November 22, 1898.

Application filed April 18, 1898. Serial No. 678,085. Term of patent 7 years.

To all whom it may concern:

Be it known that I, WILLIAM C. CAMENISCH, a citizen of the United States, residing at Chicago, in the county of Cook and State of Illinois, have invented and produced a new and original Design for Fireplace-Fronts, of which the following is a specification, reference being had to the accompanying drawings, forming a part thereof.

10 This invention relates to a new and original design for fireplace-fronts; and the leading feature of the design consists in a central ornamental panel containing in low relief allegorical figures of night and morning, surrounded by a border of ornamental work.

15 My design is illustrated in the accompanying drawings, in which—

Figure 1 represents an elevation of a fireplace-front embodying my invention. Fig. 2 is a vertical sectional view taken on the line 2 2 of Fig. 1, and Fig. 3 is a transverse sectional view taken on the line 3 3 of Fig. 1.

In the said drawings, A indicates the central panel, which has produced thereon in low relief the allegorical figures of night and morning. Above this panel is a hood B, of closed ornamental work, and below the same is a band C, of closed ornamental work. The base of the front is occupied by a section or panel D, of open geometrical work, and the 25 sides thereof are ornamented by pillars E, decorated with spirally-arranged flutings and resting upon pediments F, which are vertically fluted. The upper part of the front consists of a panel or section G, which is or- 30 namented with shell and branch designs.

I claim—

The design for a fireplace-front as herein shown and described.

WILLIAM C. CAMENISCH.
